US0D1024785S

(12) **United States Design Patent** (10) Patent No.: **US D1,024,785 S**
(45) Date of Patent: ** Apr. 30, 2024

(54) **BOTTLE**

(71) Applicant: **Diageo North America, Inc.**, New York, NY (US)

(72) Inventors: **Jennifer Brooke Hartford**, Brooklyn, NY (US); **John-Paul David Elliott**, Sleepy Hollow, NY (US)

(73) Assignee: **DIAGEO NORTH AMERICA, INC.**, New York, NY (US)

(**) Term: **15 Years**

(21) Appl. No.: **29/796,706**

(22) Filed: **Jun. 25, 2021**

(51) LOC (14) Cl. **09-01**

(52) U.S. Cl.

USPC **D9/544**

(57) **CLAIM**

The ornamental design for a bottle, as shown and described.

DESCRIPTION

FIG. 1 is a front perspective view of a bottle showing our new design;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top plan view thereof; and,

FIG. 7 is a bottom plan view thereof.

The broken lines are shown for the purpose of illustrating parts of the bottle that form no part of the claimed design. The dash-dot-dash broken lines illustrate boundaries that form no part of the claimed design.

1 Claim, 6 Drawing Sheets
